UNITED STATES PATENT OFFICE.

ERNEST N. HUMPHREY, OF NEW BRITAIN, CONNECTICUT.

BUCKLE.

Application filed July 2, 1924. Serial No. 723,664.

To all whom it may concern:

Be it known that I, ERNEST N. HUMPHREY, a citizen of the United States of America, residing at New Britain, Connecticut, have 5 invented a new and useful Buckle, of which the following is a specification.

My invention relates to a belt buckle.

It is the principal object of the invention to provide a buckle which, while providing 10 for firmly gripping the belt, is simple in construction and may be manufactured at small cost.

It is a further object to provide a buckle with an extended gripping surface for the 15 free end of the belt.

It is a further object to provide a buckle having means for reinforcing or supporting the gripping portion of the gripping plate.

In the drawings which show, for illustrative purposes only, a preferred form of 20 the invention—

Fig. 1 is a rear view of a buckle assembled with a belt and illustrating features of my invention;

Fig. 2 is a central longitudinal section 25 through the buckle shown in Fig. 1.

Fig. 3 is view similar to Fig. 2 illustrating a slightly modified form.

Fig. 4 is sectional view taken substantial- 30 ly in the plane of the line 4—4 of Fig. 2.

In the preferred form shown in Figs. 1, 2 and 4, 5 indicates the front plate of a buckle, having rearwardly extending flanges or ears 6—6 for forming a belt passage and 35 serving as a mounting for a lever plate 7. The ears 6—6 are apertured to receive the pivot lugs 8—8 extending from the lever plate 7. The forward end 9 of the lever plate 7 is bent upwardly and indicated, for 40 a purpose to be later described. The rear end of the lever plate may be provided with angularly extending flanges or ears, such as 10.

A belt holding and gripping lever 11 is 45 pivotally mounted at 12 in the ears, such as 10, and the angularly bent end of the lever 11 adjacent the pivot mounting may be pro- 50 vided with teeth 13—13, for holding the fixed end 14 of a belt. The forward end 15 of the belt gripping plate is adapted 55 to rest upon the angularly extending front end 9 of the lever plate 7, so as to give adequate support to such free end 15. The contour of the belt gripping portion 15 preferably corresponds to that of the front plate 5, while the edge of the supporting

flange 9 is preferably straight and normally engages the outer edges only of the gripping portion 15. This construction permits a slight flexing of the end 15 and provides for a resilient engagement with the free end of a belt as shown particularly in Fig. 4. If desired, the free end of the gripping plate 11 may have an extended bearing surface 60 for engagement with the free end of the belt, and, if desired, may be provided with serrations or spaced gripping points 16—16 in order to securely grip a belt.

It will be seen that, in use, the lever plate 7 is moved downwardly as viewed in 70 Fig. 2, and the gripping plate 11 is opened out so as to permit the introduction of the fixed end 14 of the belt, after which the plate 11 is moved back to the position shown in Fig. 2, so as to securely hold the fixed 75 end of the belt. The forward or free end of the belt may then be passed in between the front plate 5 and the gripping portion 15 of the gripping plate, after which the lever plate 7 is moved into the belt gripping 80 position shown in full lines in Fig. 2, in which position the free end of the belt will be tightly gripped between the front plate 5 and the gripping portion 15 on the gripping plate.

The extended bearing surface on the free 85 end of the gripping plate 11 serves to securely hold the belt in position, without unduly compressing or cutting any part thereof, so that, a belt will be likely to 90 wear longer than with the ordinary type of gripping lever, which grips the belt over only a very small area. The parts are all 95 relatively cheap to manufacture, and the entire device may be readily and quickly assembled.

In the form shown in Fig. 3, the lever plate 7' is pivotally mounted on ears such as 6' extending rearwardly from the front plate 5'. The forward end 9' of the lever plate is angularly bent upwardly to form 100 a belt gripping member. A belt gripping plate 11' is pivotally mounted on ears such as 10' extending from the lever plate 7'. The rear end of the plate 11' may be toothed 105 to securely hold the fixed end of a belt while the free end 17 is bent up angularly to form a second belt gripping member. The intermediate portion of the plate 11' rests upon and is supported in proper position by the 110 fixed end of the belt. When the parts are in operative position as shown in Fig. 3 the

two spaced apart belt gripping parts 9' and 17 serve to securely hold the free end of a belt in adjusted position.

While I have shown preferred forms of the invention, I do not wish to be strictly limited to the exact form shown, since slight changes may be made within the scope of the invention as defined in the appended claims.

19 I claim:

1. In a buckle, a front plate having rearwardly extending flanges, a lever plate pivotally mounted in said rearwardly extending flanges and a belt gripping and holding plate pivotally mounted at the free end of said lever plate, said belt holding and gripping plate serving to hold the fixed end of a belt adjacent the pivotal mounting, the opposite end of said belt holding and gripping plate serving to contact with said lever plate and having an extended bearing surface for engagement with the free end of a belt for holding the same in adjusted position.
- 25 2. In a buckle, a front plate having rearwardly extending flanges, a lever plate pivotally mounted on said rearwardly extending flanges, said lever plate being angularly bent to form a lip extending upwardly therefrom, and a belt gripping plate pivotally mounted at the rear end of said lever plate and serving to hold the fixed end of a belt, the forward end of said gripping plate having an extended bearing surface for en-

gagement with the free end of a belt for holding the latter in adjusted position, said angularly bent portion on said lever plate serving to engage beneath the gripping portion of said gripping plate for supporting the same.

40 3. In a buckle, a front plate having rearwardly extending flanges thereon, a lever plate pivotally mounted on said flanges, an upwardly extending portion on said lever plate adjacent the pivotal mounting thereof, said lever plate having ears thereon, and a belt gripping plate pivotally mounted on the ears of said lever plate and serving to hold the fixed end of a belt thereon, one end of said gripping plate having an extended 45 bearing surface for engagement with the free end of a belt for holding the same in adjusted position, the upwardly extending portion on said lever plate serving to engage beneath and support the gripping portion of said gripping plate.

4. In a buckle, a front plate, a lever plate pivotally mounted thereon, and a belt gripping plate pivotally mounted on said lever plate and serving to hold the fixed end of a belt thereon, said lever plate contacting with the free end of said belt gripping plate for supporting the latter, said belt gripping plate at a point adjacent the point of contact with said lever plate serving to hold a 55 belt in adjusted position.

60 ERNEST N. HUMPHREY.
